CURRENT COLLECTOR

Bernard F. Langer, Pittsburgh, Pa., assignor to
Westinghouse Electric Corporation, East Pitts-
burgh, Pa., a corporation of Pennsylvania

Application December 12, 1945, Serial No. 634,547

4 Claims. (Cl. 191—55)

1

My invention relates, generally, to current collectors and it has reference, in particular, to current collectors of the pantograph type.

Generally stated, it is an object of my invention to provide an improved current collector which is simple and inexpensive to manufacture and is efficient in operation.

More specifically, it is an object of my invention to provide for mounting a shoe on a current collector of the pantograph type with an effective center of rotation above the contact surface of the shoe.

Another object of my invention is to provide for mounting a current collector shoe by means of a closed pivotal link structure.

It is also an object of my invention to provide for improving the operating characteristics of shoes on current collectors of the pantograph type.

Yet another object of my invention is to provide for reducing the stubbing action of shoes on current collectors of the pantograph type.

An important object of my invention is to provide for reducing the aerodynamic lift of current collector shoes.

A further object of my invention is to provide for pivotally mounting current collector shoes on a trapezoidal link pivot support having an effective pivot point above the contact surface of the shoe with a trolley conductor.

Other objects will, in part, be obvious and will, in part, be explained hereinafter.

In accordance with one embodiment of my invention, a current collector shoe may be pivotally mounted on supports of a pantograph structure by means of pairs of pivotal link members connected to the supports and to the shoe adjacent each end thereof and inclined upwardly and inwardly toward each other so as to produce an effective center of rotation of the shoe relative to the supports which is above the contact surface of the shoe with the trolley conductor. The link members are enclosed by a cover secured about the lower side of the shoe to provide a symmetrical section for reducing the aerodynamic lift of the shoe.

For a more complete understanding of the nature and scope of my invention, reference may be made to the following detailed description which may be studied in connection with the accompanying drawing, in which:

Figure 1 is a front elevational view of a current collector shoe of the type now extensively used;

Fig. 2 is an end elevational view, partly in

2

section, of a current collector of the pantograph type illustrating the invention in one of its forms; and

Fig. 3 is an enlarged partial and elevational view of a current collector similar to that of Fig. 2, showing a modification of the invention.

Referring to Figure 1, the reference numeral 10 may denote, generally, an elongated channel-shaped current collector shoe of a type now commonly used with current collectors of the pantograph type. The current collector shoe 10 may be supported on a pantograph structure (not shown) by means of support levers 12 which may be pivotally connected to the shoe by means of pins 13. With such a shoe, the frictional drag of the conductor tends to rotate the leading edge of the shoe against the conductor to produce a stubbing action. Aerodynamic lift causes the channel section to raise the conductor, thus increasing the stresses therein.

Referring to Fig. 2, the reference numeral 14 may denote, generally, a current collector of the pantograph type having shoes 15 of a type generally similar to that shown in Fig. 1, and which are disposed to be supported on a pantograph structure 16 for engaging a trolley conductor 17. The shoes 15 may be mounted on the pantograph structure 16 by means of support levers 19 which may be pivotally connected by pins 18 to a support member 20 with springs 21 around the pins to hold the lever and shoe assembly up in the correct operating position. The support member 20 is connected to the pantograph structure 16 by means of pins 22 which may be movably positioned in slots 23 in the support member.

In order to provide for pivotally connecting the shoes 15 to the support levers 19, means such as the link members 25 may be provided. The link members 25 may be pivotally connected to the shoes 15 adjacent each end thereof, at predetermined points spaced in the longitudinal direction of the trolley conductor 17 by means of pins 27. The other ends of the link members 25 may be pivotally connected by pins 27 to enlarged heads 28 on the support levers 19.

By spacing the points of connection of the link members 25 to the heads 28 further apart than the points of connection to the shoe 15, the link members 25 may provide in conjunction with the shoe 15 and heads 28, closed pivotal link structures in which the link members 25 are inclined inwardly toward each other to form a trapezoid. This arrangement provides an effective center of rotation for the shoe 15 which

is at the intersection of axes drawn through the connecting pins 27 of the two link members, and which is positioned above the contact surface of the shoe 15 with the conductor 17.

Accordingly, frictional engagement of the shoe 15 with the conductor 17 as the shoe moves from right to left, tends to rotate the shoe in a counterclockwise direction about the effective pivot point. This results in the leading edge of the shoe, which may be assumed to be the left hand edge for movement of the current collector from right to left, being moved away from instead of toward the conductor 17. Stabbing action of the shoe is thus prevented, since the frictional force between the shoe and the conductor is reduced by such rotation of the shoe.

In order to further improve the operating characteristics of the shoe 15, means such as the cover 30 may be provided. The cover may comprise a substantially channel-shaped member having a central portion 32 extending between the depending edges of the shoe 15 and having openings 33 therein for receiving the support lever 19. The upstanding edge portions 34 of the cover may be secured to the depending edges of the shoe 15 in any suitable manner, and may be recessed in recesses 35 extending along the outer edges of the depending edge portions so as to provide a substantially symmetrical section for the shoe 15 having rounded edges which present a minimum of aerodynamic drag.

Referring to Fig. 3, it will be seen that a predetermined amount of resilience may be provided in connection with the link members 25 by utilizing means such as the springs 38 which may be operatively connected between the link members 25 and the head 28 of the support lever 19. By positioning the springs 38 about the support pins 27, the link members 25 may be resiliently biased inwardly toward each other so as to stabilize pivotal action of the shoe 15 relative to the support lever 19.

From the above description and the accompanying drawing, it will be apparent that I have provided in a simple and effective manner for improving the operating characteristics of current collector shoes such as used with current collectors of the pantograph type. By utilizing pivotal link members in the manner hereinbefore described, the current collector shoes may be provided with an effective center of rotation sufficiently above the contact surface of the shoe to prevent stabbing of the shoe relative to the trolley conductor. Since the frictional drag between the shoe and the conductor is reduced by rotation of the leading edge of the shoe away from the conductor, dynamic operation of the current collector shoe is therefore greatly stabilized. By enclosing the lower side of the current collector shoe, the aerodynamic lift of the shoe is greatly reduced, so that lifting of the conductor 17 is minimized at relatively high speeds. Accordingly, the stresses in the trolley conductor are greatly reduced.

Since certain changes may be made in the above-described construction, and different embodiments of the invention may be made without departing from the spirit or scope thereof, it is intended that all matter contained in the above description and shown in the accompanying drawing shall be considered as illustrative and not in a limiting sense.

I claim as my invention:

1. A current collector comprising, an elongated shoe disposed transversely of and having an upper surface to engage a conductor, a support adjacent each end of the shoe, a pair of levers pivotally connected to the shoe and to the support adjacent each end, said levers being spaced longitudinally of the conductors and inclined inwardly and upwardly to provide an effective pivot point beyond the point of engagement between the shoe and the conductor, and a cover secured to the shoe enclosing the levers and the lower side of the shoe, said cover having a lower surface substantially symmetrical with the upper surface of the shoe.

2. A current collector comprising, an elongated shoe having an upper surface with rounded leading and trailing edge portions for engaging a conductor with depending flanges along the sides, support means including pairs of link members pivotally connected to the shoe on the lower side and to support means at predetermined spaced points to provide an effective pivot point on the conductor side of the upper surface, and a channel-shaped housing positioned on the lower side of the shoe having openings for the support means and upwardly projecting flanges secured to the depending flanges of the shoe, said housing having rounded leading and trailing edge portions to provide with the shoe a symmetrical transverse section.

3. A current collector comprising, a channel-shaped shoe having a relatively flat continuous surface for engaging a conductor and depending front and rear flanges, a pair of upwardly and inwardly inclined link supports pivotally connected to the underside of the shoe between the flanges and to a support in spaced relation longitudinally of the conductor, and a channel-shaped cover secured to the underside of the shoe enclosing said link supports and providing a substantially symmetrical enclosed vertical cross-section.

4. A current collector comprising, a shoe having a contact surface for engaging a conductor, support means, and a pair of link members pivotally connecting the shoe and the support at predetermined points spaced in the longitudinal direction of the conductor, the points of connection on the support means being spaced further apart than the points on the shoe, and helical springs positioned at the points of connection of the link members and support means resiliently biasing the link members in opposite senses.
